GEORGE T. JACOCKS, STANLEY J. CHUTE, AND JAMES B. FORBES, OF NEW YORK, N. Y.,
ASSIGNORS TO ALCO PRODUCTS, INCORPORATED, OF NEW YORK, N. Y., A CORPORATION OF DELAWARE

HEAT EXCHANGER

Application filed April 22, 1932. Serial No. 606,852.

Our invention relates to heat exchangers to the respective channel members. Each and more particularly to a high pressure, high temperature heat exchanger adapted for use in connection with the pyrolytic process-
5 ing of hydrocarbon oils.

One object of our invention is to provide a novel construction in which no steel castings are used adapted to sustain high pressures and high temperatures.

10 Another object of our invention is to provide a construction in which the minimum number of field connections must be made.

Another object of our invention is to provide a unit which is easily accessible for
15 cleaning and inspection.

In the accompanying drawings which form part of the instant specification and are to be read in conjunction therewith and in which like reference numerals in the various views
20 are used to indicate like parts;

Figure 1 is an elevation of our heat ex-
changer partly in section.

Figure 2 is a plan view of our heat ex-
changer.

25 Figure 3 is a sectional view partially bro-
ken away, taken on a line 3—3 of Figure 2.

Figure 4 is a sectional view taken on a line
4—4 of Figure 3.

30 In general, our invention consists in a heat exchanger having a plurality of channel members welded to a single channel flange so as to form an integral channel member. The liquid entrance and exit connections are car-
ried by the channel member. Bolted to the

35 channel member are a plurality of shells formed in two parts, the lower portions of the shells being removable in parts without breaking the vapor connections for inspec-
tion and cleaning. Each shell is provided
with a separate condensate drain and houses
a tube bundle. The tubes are secured to tube
sheets in the channel members at one end and
at their other ends to a floating header. There
is but a single floating header in each shell.

40 No longitudinal baffles are used. Transverse
baffles carried by the tubes are fitted.

More particularly referring now to the
drawings, channel flange 1 has welded thereto
a plurality of channels 2 connected to each
50 other by pipe connections 3 which are welded

to the respective channel members. Each
channel member is hogged out of a single
billet of silicon killed steel having integral
partition members 4 therein to form liquid
passes. The partition members 4 may, if de-
55 sired, be separate pieces welded integrally
with the channel members. The construction
is such as to withstand the pressure alone, the
partition members giving additional support
and furnishing a means to secure the cover
60 plates 5 thereto. The cover plates 5 are also
hogged out of silicon killed steel and are
secured to the channel members 2 by means
of short stud bolts 3 and 4 which enter the
partition members and channels respectively.

65 It will be observed that the channel members
together with their cover plates form a plu-
rality of stationary sub-headers. The sub-
headers being welded to a plate 1 form a
composite stationary header. We prefer to
70 term the plate 1 the "flange member". The
stationary header assembly will be referred
to as the "stationary header", while the chan-
nel members and their cover plates will be
75 termed "sub-headers". Liquid inlet pipe 6 is
welded to one channel member and liquid out-
let pipe 7 is welded to the last channel mem-
ber. The lower portions of the channel mem-
ber are made of unusual thickness to allow
80 for corrosion and form heavy tube sheets
capable of withstanding the high pressures
with which the heat exchanger is designed to
be used. Welded to channel flange 1 are lugs
84 adapted to support our heat exchanger.

85 Bolted to channel flange 1 are a plurality of
shells which house the two bundles. The
shells are formed in two parts, namely, upper
parts 9 which have bolted thereto lower parts
10. The vapor inlet connection 11 and the
89 vapor outlet connection 12 are secured to the
upper shell portions 9. The lower shell por-
tions are bolted to shell portions 9 and are
provided at their lower ends with conden-
sate drain connections 13. The lower shell
95 portions 10 are provided at their lower ends
with vapor pass connections 14. The upper
portion of adjacent shell portions 10 are
joined by brackets 15 so that two adjoining
lower shell portions are secured to each other
99 by brackets 15 and vapor pass connections 14.

By reference to Figure 1, it will be obvious that if bolts 16 which secure the lower shell portions 10 to the upper shell portions 9 are removed, that a pair of lower shell portions 5 may be dropped free to expose the tube bundles 17 to inspection. If desired, vapor connections 14 may be made removable so that individual shells may be dropped for inspection if desired. The tube bundles 17 are provided with transverse baffles 18 which are carried by the tubes and not by the shells so that the shells may be readily removed. No longitudinal baffles are used, each shell forming but a single vapor pass. By using this form 10 of construction, coking and carbon depositions are avoided. The tubes 19 are secured to the lower portions of the channel members 2 which form upper tube sheets and are secured at the lower ends to floating headers 20. 15 Floating headers 20 comprise floating channel members 21 and cover plates 22. The channel members 21 are similar to the upper channel members 2, being hogged out of a single billet of silicon killed steel. The cover plates 22 are likewise hogged out of silicon killed steel and provided with integral partition members 23. The arrows in the drawings indicate the flow of the liquid and vapor through our heat exchanger. Shells 10 are 20 fitted with lugs 24 for lifting and handling the shells 10. By removing cover plates 5 the inside of the tubes may be readily inspected. 25 In operation, the liquid enters liquid inlet 6 into the first liquid pass of channel member 2 and flows downwardly into the first liquid pass of the floating header, thence upwardly to the second liquid pass of the channel member, thence downwardly to the second liquid pass of the floating header, thence 30 upwardly to the third liquid pass of the channel member. This liquid flow is repeated for each channel and its respective floating header until the liquid leaves through liquid outlet 7. The vapors enter 35 vapor inlet 11, flow downwardly through the first shell, thence upwardly through the second shell, thence downwardly through the third shell, thence upwardly through the fourth shell and leave through vapor outlet 40 12. Thus it is seen that there is but one vapor pass within each shell and the direction of the vapor flow is in general counter flow relation to the direction of the liquid flow, insuring an efficient heat exchange. 45 Our construction has many advantages. We are enabled to eliminate the use of any steel castings whatever. Our construction is able to withstand high pressures and extremely high temperature, the individual 50 floating headers being designed for sufficiently small tube bundles so that the temperature gradient within each shell is not excessive. Our construction is of comparatively light weight. Due to the fact that 55 there is but a single vapor pass through each

shell, no longitudinal baffles are necessary, which decreases the tendency to the formation of coke and carbon deposits. The elimination of longitudinal baffles, furthermore, makes the shell easy of removal so that the tubes may be cleaned and inspected with minimum difficulty. The only high pressure connections necessary to be made in the field are the inlet and outlet channel connections, inasmuch as the connections between the various elements of the exchanger are made in the shop. This is true, likewise, of the vapor connections. The compactness of the complete unit and the accessibility for cleaning are apparent. The use of integral partition members renders the use of longer stay bolts unnecessary. Only short stay bolts are used which are tapped into the integral partitions between liquid passes and these are continuous with the circle stud bolts which hold the channel cover on around its circumference, insuring leak proof joints. The entire unit is supported by the lugs 8 and is easily installed. 70 75 80 85 90

It will be understood that certain features and sub-combinations are of utility and may be employed without reference to other features and sub-combinations. This is contemplated by and is within the scope of our claims. It is further obvious that various changes may be made in details within the scope of our claims without departing from the spirit of our invention. It is, therefore, to be understood that our invention is not to be limited to the specific details shown and 95 100 105 described.

Having thus described our invention, what we claim is:

1. A high pressure, high temperature heat exchanger adapted for use in the pyrolytic processing of hydrocarbon oils, comprising in combination a flange member, a plurality of sub-headers integral therewith, tube bundles communicating with the respective sub-headers, a floating header communicating with each tube bundle, separate shells surrounding each tube bundle and removably secured to said flange member, communicating means between the sub-headers, communicating means between the shells, a liquid inlet to one sub-header, a liquid outlet from one sub-header, whereby liquid is adapted to flow through said respective sub-headers, tube bundles and floating headers in succession, a vapor inlet to one shell, a vapor outlet from one shell whereby vapor is adapted to flow through said shells in succession in heat exchange relationship with said liquid. 110 115 120

2. A high pressure heat exchanger comprising in combination a stationary header, a plurality of floating headers, a plurality of tube bundles extending between the stationary header and the respective floating headers, a plurality of separate shells surrounding the respective tube bundles and 125 130

- floating headers and a condensate drawoff connection for each shell.
3. A high pressure heat exchanger comprising in combination a stationary header, having a pair of stationary sub-headers, a pair of floating headers, a pair of tube bundles extending between the respective stationary sub-headers and floating headers, a pair of separate shells surrounding the respective tube bundles, said shells being formed in two parts, a vapor inlet connection in one of the upper shell parts, a vapor outlet connection in the other of said upper shell parts, a vapor connection between said lower shell parts and a bracket connecting said lower shell parts whereby the lower shell parts may be removed together for tube bundle cleaning and inspection, without breaking the vapor inlet and outlet connections.
- 10 4. A heat exchanger as in claim 2 wherein said stationary header comprises a flange plate and sub-header members welded thereto, a liquid pass pipe between said sub-header members, cover plates for said sub-header members, said members being hogged out of a single billet of silicon killed steel and having integral liquid pass partitions therein.
- 15 5. A heat exchanger as in claim 2 wherein said floating headers comprise members hogged out of single billets of silicon killed steel, integral liquid pass partitions in said members and cover plates secured thereto.

6. A heat exchanger as in claim 2 in which the sole supporting means for the heat exchanger comprises lugs integral with said stationary header.
7. A heat exchanger as in claim 2 in which said shells comprise upper and lower parts, vapor inlet and outlet connections secured to said upper parts, whereby said lower shell parts may be removed for tube inspection without breaking said vapor inlet and outlet connections.
- 70 8. A heat exchanger as in claim 2 wherein said tube bundles are provided with transverse baffles secured thereto and unattached to the shells, whereby said shells are rendered readily removable.
- 80 9. A high pressure heat exchanger comprising in combination a stationary header, a plurality of floating headers, a plurality of tube bundles extending between the stationary header and the respective floating headers, a plurality of separate shells surrounding said tube bundles and forming a single pass for the travel of vapors therethrough in heat exchange relation to liquid passing through the tubes of the tube bundles, whereby said vapors are condensed in said separate shells, and condensate drawoff connections for each shell.
